4 Sheets-Sheet 1

Diagram illustrating a complex electrical circuit, likely a relay control system, with various components and connections labeled with numbers. The circuit is organized into several vertical columns and includes a power source at the bottom left.

Power Source: A battery symbol with a switch labeled 11 is connected to a coil labeled 10. A switch labeled 12 is connected in parallel with the coil 10.

Relay Control: A relay labeled 17 is controlled by a switch labeled 20. The coil of relay 17 is connected in parallel with the coil of relay 10. The contacts of relay 17 are connected to a switch labeled 19.

Central Column: A central vertical column contains a switch labeled 31, a switch labeled 50, and a switch labeled 58. The coil of relay 40 is connected in parallel with the coil of relay 10. The contacts of relay 40 are connected to a switch labeled 24.

Top Row: The top row of the circuit includes a switch labeled 32, a switch labeled 33, a switch labeled 34, and a switch labeled 35. The coil of relay 41 is connected in parallel with the coil of relay 10. The contacts of relay 41 are connected to a switch labeled 42.

Bottom Row: The bottom row of the circuit includes a switch labeled 51, a switch labeled 52, a switch labeled 53, and a switch labeled 59. The coil of relay 61 is connected in parallel with the coil of relay 10. The contacts of relay 61 are connected to a switch labeled 62.

Right Column: The right column of the circuit includes a switch labeled 63, a switch labeled 64, a switch labeled 65, and a switch labeled 66. The coil of relay 70 is connected in parallel with the coil of relay 10. The contacts of relay 70 are connected to a switch labeled 71.

Left Column: The left column of the circuit includes a switch labeled 72, a switch labeled 73, a switch labeled 74, and a switch labeled 75. The coil of relay 73 is connected in parallel with the coil of relay 10. The contacts of relay 73 are connected to a switch labeled 76.

Bottom Left: A switch labeled 80 is connected in parallel with the coil of relay 10. The contacts of switch 80 are connected to a switch labeled 81.

Bottom Right: A switch labeled 91 is connected in parallel with the coil of relay 10. The contacts of switch 91 are connected to a switch labeled 92.

Bottom Center: A switch labeled 93 is connected in parallel with the coil of relay 10. The contacts of switch 93 are connected to a switch labeled 94.

Bottom Left: A switch labeled 95 is connected in parallel with the coil of relay 10. The contacts of switch 95 are connected to a switch labeled 96.

Bottom Right: A switch labeled 97 is connected in parallel with the coil of relay 10. The contacts of switch 97 are connected to a switch labeled 98.

Bottom Center: A switch labeled 99 is connected in parallel with the coil of relay 10. The contacts of switch 99 are connected to a switch labeled 100.

Bottom Left: A switch labeled 101 is connected in parallel with the coil of relay 10. The contacts of switch 101 are connected to a switch labeled 102.

Bottom Right: A switch labeled 103 is connected in parallel with the coil of relay 10. The contacts of switch 103 are connected to a switch labeled 104.

Bottom Center: A switch labeled 105 is connected in parallel with the coil of relay 10. The contacts of switch 105 are connected to a switch labeled 106.

Bottom Left: A switch labeled 107 is connected in parallel with the coil of relay 10. The contacts of switch 107 are connected to a switch labeled 108.

Bottom Right: A switch labeled 109 is connected in parallel with the coil of relay 10. The contacts of switch 109 are connected to a switch labeled 110.

Bottom Center: A switch labeled 111 is connected in parallel with the coil of relay 10. The contacts of switch 111 are connected to a switch labeled 112.

Bottom Left: A switch labeled 113 is connected in parallel with the coil of relay 10. The contacts of switch 113 are connected to a switch labeled 114.

Bottom Right: A switch labeled 115 is connected in parallel with the coil of relay 10. The contacts of switch 115 are connected to a switch labeled 116.

UNITED STATES PATENT OFFICE.

RODNEY G. RICHARDSON, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed November 23, 1920. Serial No. 426,011.

To all whom it may concern:

Be it known that I, RODNEY G. RICHARDSON, a citizen of the United States of America, and a resident of Chicago, Cook County, 5 and State of Illinois, have invented certain new and useful Improvements in Automatic Telephone Systems, of which the following is a specification.

The present invention relates in general 10 to automatic telephone systems in which directly controlled automatic switches are employed to establish connections between calling and called subscribers' lines; and the principal object is to provide a new and improved system of finder switches for extending calling lines into connection with trunk lines, the finder switches used having both primary and secondary selecting movements, and being adapted to perform both movements simultaneously.

A further object is to provide a new and improved first selector switch adapted for use in exchanges where the trunking capacity required exceeds 1,000 or 10,000 lines, 15 but does not exceed twice the figures named, the new switch being adapted to perform a group selecting operation controlled by relays in which either one of two groups of twenty-five trunk lines each may be selected, 20 and a trunk selecting operation in which the first idle trunk in the selected group is taken for use.

A third object is to provide a selector switch, which may be a first, second, or 25 third selector, having improved circuit arrangements and characterized especially by a test circuit arrangement in which the idle condition of trunk lines is indicated by a battery potential, instead of a ground potential.

The improved selectors above referred to are not claimed herein but are claimed in my divisional application, Serial No. 15,435, filed March 14, 1925.

The means by which the foregoing and other useful objects are obtained will be described fully in the detailed specification which is to follow, reference being had to the accompanying drawings forming a part thereof.

In the drawings, Figs. 1, 2, and 3 are circuit diagrams of the essential apparatus in a telephone system embodying the principles of the invention. Fig. 4 is a conventional drawing showing certain mechanical details

of the finder switch. Fig. 5 is a different view of certain parts shown in Fig. 4.

Referring first to Figs. 1, 2, and 3, these circuit diagrams show a plurality of serially related automatic switches which may be 60 used to establish a talking connection between the substation A, Fig. 1, and the substation A', Fig. 3. The series of switches comprises the finder switch F, Fig. 1, the first and second selectors D and E, Fig. 2, 65 and the connector H, Fig. 3.

The automatic telephone substations A and A' are of the usual type and have the usual talking instrumentalities and calling devices for controlling the central office 70 switches. At the exchange each line is provided with a combination line and cut-off relay. In the case of the line of substation A, this individual relay is indicated by the reference character 16. The lines are divided into groups of 100 lines each in accordance with the capacity of the connector and finder switches, and in addition to the individual line relays there are 10 tens relays 75 and 10 units relays for each group, each of 80 the tens relays being common to all of the lines of the group which terminate in the same level and which, therefore, have the same tens digit in their telephone numbers, and each of the units relays being common 85 to all of the lines of the group which have the same final digit in their telephone numbers. The tens and units relays associated with the line of substation A are indicated 90 by the reference characters 17 and 18, respectively. It may be stated that the function of the tens and units relays is to indicate by their joint action the calling condition of any calling line in the banks of the finder switches.

The finder switch F, the selector E, and the connector H are of the well known Strowger vertical and rotary type so far as their mechanical construction is concerned, and hence will not need to be described in detail. The construction of the finder switch, however, has been changed somewhat in order to permit it to perform its vertical and rotary selecting operations simultaneously, and these modifications will be explained shortly. The circuits of all the switches named are shown complete in the drawings and will be fully described.

The first selector D is similar in construction to a well known type of rotary line 110

switch. It has two sets of wipers and a double bank with 25 contact sets associated with each set of wipers. The wipers normally rest on the contact sets last used and move in a forward direction only. The primary or group selection performed by this first selector is controlled entirely by means of relays, that is, there is no primary stepping movement, and the group selecting operation consists merely in selecting one or the other of the two sets of wipers. The circuits are shown in full, and will be described.

Referring now to Fig. 4, the mechanical construction of the finder switches will be considered a little more in detail. In general these switches are similar to the well known Strowger vertical and rotary switches, as stated, and have the usual switch frame, banks, and operating magnets. The essential differences, or modifications, have to do principally with the shaft and wipers, and are rendered necessary by the fact that the vertical and rotary selecting operations are to be performed simultaneously. The drawing, therefore, shows only the lower portion of the shaft of one of these finder switches, together with the wipers and associated sets of bank contacts. The drawing is not a working drawing. It is more or less conventional, and is intended only to illustrate the theory of operation. To proceed, the shaft 300 corresponds in general to the usual switch shaft in this type of switch, and has the usual vertical ratchet teeth indicated by the reference character 301. These ratchet teeth are cut in a cylindrical hub or sleeve which is not fixed rigidly to the shaft, but on the contrary is rotatable thereon, being held in place so far as longitudinal movement on the shaft is concerned by a collar 320. The shaft is broken away just above the collar 320 and as there is nothing new in the construction above this point, it will be understood that the omitted parts are similar in form and function to those usually found in this type of switch. The shaft is rotated by means of the rotary ratchet wheel 302. This rotary ratchet wheel does not rise with the shaft in its vertical movement as is the usual practice, but is loosely mounted on the shaft and has a hub 303 which fits in a bearing 304, which in turn may be secured to the switch frame in any suitable manner. During the vertical operation of the switch, then, the shaft simply rises through the ratchet wheel 302 and the latter remains stationary. The rotary ratchet wheel 302 turns the shaft by means of a rod 307. This rod extends vertically between two horizontal members 305 and 306, which are securely clamped to the shaft 300 by means of set screws, and fits loosely in a hole near the outer circumference of the rotary ratchet

wheel 302. It will be seen now that since the vertical hub carrying the teeth 301 is rotatable upon the shaft and since the shaft is movable longitudinally relative to the rotary ratchet wheel 302, the shaft can be raised vertically and rotated at the same time.

In view of the above it will be evident that the ordinary wiper construction cannot be used, since if the wipers were permanently attached to the shaft 300 they would prevent the simultaneous longitudinal movement and rotation of the shaft. In order to overcome this difficulty the usual private or test wiper 91, and line wipers 90 and 92 are mounted on a tube or sleeve 312, which may be considered as an auxiliary shaft, and is rotatably mounted on the main shaft 300. A pin 313 passes through a hole in the main shaft just below the auxiliary shaft and prevents the latter from slipping down. The horizontal member 310 is clamped to the auxiliary shaft near the top and is normally held against the downwardly projecting arm 309 by means of a small clock spring which is enclosed within the circular cup spring casing 308. One end of the spring is attached to the casing and the other end is attached to the top of the auxiliary shaft, while the casing itself is rigidly secured to the main shaft 300. This arrangement, including the casing 308 and the spring enclosed therein, is similar to the cup spring assembly generally used at the top of the shaft. At the right the horizontal member 310 carries a roller 321 which is normally locked behind the forward extending latch portion of armature 322. Fig. 5 shows how the roller 321 and armature 322 look when viewed from the top, and with the aid of this view the construction will be readily understood. When the vertical and rotary magnets are operated simultaneously, the former raises the shaft vertically by means of the vertical teeth 301, and the latter rotates the shaft by means of the rotary ratchet wheel 302. The main shaft 300 rotates within the vertical hub carrying the teeth 301 and slides longitudinally through the rotary ratchet wheel 302. The auxiliary shaft 312 rises vertically with the main shaft but does not rotate, being prevented from so doing by the engagement of the roller 321 with the latch portion of armature 322. While the vertical movement continues, then, the roller 321 will simply ride up on this latch and the rotation of the main shaft will have no effect other than to tension the cup spring connecting the two shafts. At the end of the vertical movement, the magnet 52 associated with armature 322 is automatically energized, and the roller 321 is released. As a result the auxiliary shaft is instantly rotated around on the main shaft until the member 310 strikes against the arm

309 when the two shafts will be in their normal relation to each other. If the rotary selecting movement has already stopped the switch wipers will now be in engagement 5 with the proper set of contacts, but if the rotary selecting movement has not been completed it will continue as usual, and both main and auxiliary shafts will be rotated simultaneously and as a single unit. It 10 should be mentioned that the member 306 carries a pair of contact springs 54 and 55, which are normally closed. These springs separate as soon as the main shaft starts to rotate and are closed again when the auxiliary shaft resumes its normal position after being released by armature 322.

The test wipers are indicated by the reference characters 93 and 94, the former being the tens or vertical wiper, while the latter is the units or rotary test wiper. The rotary test bank consists of eleven test contacts, ten of which correspond in position to the ten line and private contacts in each of the levels in the banks above, while the first 25 is set slightly ahead of the first of the others, and is engaged by the test wiper 94 when in normal position. The lower semi-circular clamping member 314 is constructed somewhat differently from ordinary practice and 30 has a projecting arm 315 at the left which is bent at right angles and extends vertically along side of the line and private banks. This vertical member 315 carries a strip of 35 ten vertical test contacts which are held in position so that they are engaged by the test wiper 93. Wiper 93 is adapted to be moved vertically with the auxiliary shaft 312, but does not rotate with the shaft. The rotary test wiper 94 is mounted on the main 40 shaft 300 and although it is loosely mounted upon the said shaft, it is rotated whenever the shaft turns by means of the pin 317, which fits in a slot 318 in the main shaft. Wiper 94, however, does not rise vertically, 45 being held in position by the cross bar 316 attached to the lower ends of the bank rods. The lower hub of the wiper assembly fits in a circular bearing in this member 316 and is held loosely in place by means of 50 a lock nut.

Having given a general description of the apparatus used, the operation thereof will now be described more in detail, it being assumed for this purpose that the subscriber 55 at substation A, Fig. 1, desires to obtain a connection with a subscriber at substation A', Fig. 3. The telephone number at substation A' will be assumed to be #4567, while the telephone number at substation A 60 is #XX23.

When the receiver is removed at the calling station a circuit is completed for the tens and units relays 17 and 18, and the line relay 16 over the following path: Ground at G², 65 winding of units relay 18, resting contact

of armature 21 and the said armature, line conductor 12, to and through the telephone at substation A, conductor 11, resting contact of armature 20 and the said armature, upper winding of relay 16, and the winding 70 of the tens relay 17 to battery. Upon the closure of the above circuit relays 17 and 18 are energized, while relay 16 is operated sufficiently to close the make contact at its armature 19. This relay is marginally adjusted and when energized over the line circuit it is operated sufficiently to close the contact named, but does not open the break contacts at armatures 20 and 21. When the units relay 18 pulls up it removes ground 75 from the third test contact in the rotary test banks of all the finder switches in the group having access to the calling line, and the tens relay 17, upon energizing, removes ground from the second test contact in the vertical test banks of these finder switches. At the same time, relay 17 connects ground to the starting wire 80 which extends to the second finder switch in the group. This second finder switch is the finder switch F, and 80 assuming that the switch is now in idle condition a circuit will be completed from the grounded starting wire 80 by way of armature 60 and its resting contacts, and the winding of line relay 43 to battery. Upon energizing, relay 43 completes a circuit at its armature 68, which includes two branches, the first extending from the said armature 68 to the right by way of the winding of relay 44, armature 79 and its resting contact, 85 and the winding of the vertical magnet 47 to battery, while the second extends to the left by way of the resting contact of armature 65 and the said armature, winding of relay 45, 90 resting contact of armature 78 and the said armature, and the winding of the rotary magnet 48 to battery. At the same time as these parallel branch circuits are completed, relay 43 connects the vertical test wiper 93 to the vertical magnet circuit at a point midway between the said magnet and relay 44, 95 and also connects the rotary test wiper 94 to the rotary magnet circuit at a point midway between the said rotary magnet and relay 45. The two test wipers are connected up 100 at armature 67 and 66, respectively. 105

Whether or not the switch will operate vertically now depends upon whether or not the vertical test wiper 93 is in engagement with a grounded test contact. Since the 110 calling line is a line which terminates in the second level of the finder switch, ground has not been removed from the first of the vertical test contacts but from the second, and it follows, therefore, that relay 44 will be short circuited temporarily, while the vertical magnet 47, being supplied with direct ground by way of the vertical test wiper, 115 will be energized. By the operation of the vertical magnet the shaft and wipers are 120

raised one step, and the latter are brought opposite the second level of bank contacts. In operating, the vertical magnet closes the circuit for the interrupter relay 49 and this relay upon energizing breaks the circuit of the vertical magnet. The vertical magnet is accordingly deenergized and breaks the circuit of relay 49, which thereupon falls back and again closes the vertical magnet circuit. 5 If the second test contact in the vertical test bank is also grounded, the vertical magnet will now be operated again and the switch will be raised another step, the operation continuing in this manner as long as 10 15 20 25 30 35 40 45 50 55 60 65

the test wiper continues to engage grounded test contacts. But in the present case the calling line is terminated in the second level and the second test contact, therefore, will have no ground potential upon it. When test wiper 93 arrives at the second test contact, therefore, it will find no ground potential, the vertical magnet will not again be energized, and relay 44 being no longer short circuited, will be energized in series with the vertical magnet. Relay 44 is of very high resistance and the vertical magnet remains inoperative. Upon energizing, relay 44 disconnects the test wiper 93 from its upper winding and connects it to ground instead, in order to make the second level busy.

While the vertical magnet is raising the switch shaft vertically, as above described, the rotary magnet 48 is operating to rotate the shaft. The test contact normally engaged by the test wiper 94 is permanently grounded as indicated in the drawing, and when the circuits of the rotary magnet 48 and relay 45 are completed by the line relay 43 as previously described, relay 45 will be short circuited and the rotary magnet 48 will be operated. By the operation of the rotary magnet the main shaft of the finder switch is rotated and the rotary test wiper 94 is brought into engagement with the first of the regular test contacts. In operating, the magnet 48 closes the circuit of relay 50 which, upon energizing, breaks the rotary magnet circuit. The rotary magnet now deenergizes and breaks the circuit of relay 50, which thereupon falls back and again closes the circuit of the rotary magnet. Since the calling line is terminated in the third contact set in the second level ground has been removed from the third test contact by the units relay 18, and the first test contact will still be grounded, assuming that the first units relay is not energized by another calling line. This being the case, relay 45 will remain short circuited and the rotary magnet 48 will again be energized, with the result that the main shaft is rotated another step, and the test wiper 94 is brought into engagement with the second test contact. For the purpose of this explanation, let it be assumed now that the second line in the

sixth level, or line #XX62, is calling, in which case the second units relay will be energized and ground will have been removed from the second test contact. When the test wiper arrives at the second test contact, therefore, it will find no ground potential, the rotation of the switch will cease, and relay 45, being no longer short circuited, will energize in series with rotary magnet 48. Relay 45 is of high resistance like relay 44, and the rotary magnet is not affected. The vertical movement of the switch has already ceased, and relay 44 is now in energized position. In addition to the functions already explained relay 44 closes a circuit 70 75 80 85 90 95 100 105 110 115 120 125 130

at its armature 73 for the wiper release magnet 52 and this magnet, upon energizing, releases the auxiliary shaft so that the line and private wipers of the finder switch are instantly rotated onto the second contact set in the second level. As soon as the auxiliary shaft reaches its normal position with respect to the main shaft, contact springs 54 and 55 are closed. Two circuits may now be traced which have been closed by the joint energization of relays 44 and 45. The first of these extends from ground by way of the winding of slow acting relay 42, springs 55 and 54, armature 72 and its working contact, working contact of armature 76 and the said armature, and the winding of the rotary magnet 48 to battery. Upon the closure of this circuit relay 42 is energized. The second circuit referred to is a test circuit and extends from ground by way of the working contact of armature 77 and the said armature, armature 74 and its working contact, the upper winding of relay 41, and the normally closed contact springs controlled by armature 58 of relay 40 to the private wiper 91. At this point, however, the circuit is open, for according to the previous assumption the only two calling lines are the line of substation A which is terminated in the third contact set in the second level, and another line which is terminated in the second contact set of the sixth level. Since the line terminating in the second contact set in the second level is not calling, its line relay will not have been energized and the bank contact now engaged by the private wiper 91 will not have been connected through to the cut-off winding of the associated line relay. The test circuit described, therefore, will not be completed, and relay 41 will not be energized. When relay 42 attracts its armature 64 it prepares a circuit for its rotary magnet 48, and at its armature 65 breaks the circuit of relay 45. The latter relay, therefore, falls back, closes the rotary magnet circuit at the resting contact of its armature 76, and breaks the circuit of relay 42 at the working contact of the same armature. Being slow acting, relay 42 is not deenergized for an instant, and the rotary

magnet 48 is thus operated to rotate the shaft and wipers into engagement with the third set of contacts in the second level, test wiper 94 being moved at the same time into engagement with the third test contact in the rotary test bank. The circuits are now in the same condition as when the rotary movement of the switch was first initiated, and the rotation of the switch will be continued if necessary until the test wiper 94 locates another ungrounded test contact. But in the present case, the calling line is terminated in the third set of contacts in the second level, upon which the switch wipers are now resting, and ground has been removed from the test contact now engaged by the test wiper 94 by the operation of the units relay 18. It follows, therefore, that the rotation of the switch will again be stopped and relay 45 will again be energized. As before, circuits are now completed simultaneously for relay 42, and for the upper winding of relay 41. This time, since the private wiper 91 is now in engagement with bank contact 31, the latter circuit is completed by way of armature 19 and its working contact, and cut-off winding of relay 16 to battery. Relays 41 and 16 are accordingly energized in series, and the latter relay disconnects line conductors 11 and 12 from the tens and units relays 17 and 18 at armatures 20 and 21, respectively. Relay 41 energizes slightly before relay 42, and at its armature 62 closes a shunt around the break contact at armature 65 of the latter relay, and thus prevents opening of the circuit of relay 45. In addition relay 41 completes a circuit for the switching relay 40 which extends from ground by way of armature 69 and its working contact, armature 63 and its working contact, lower winding of relay 41, and the winding of relay 40 to battery. Upon attracting its armature 58, relay 40 disconnects private wiper 91 from the circuit including the upper winding of relay 41, and connects it instead to the circuit just established, which includes the switching relay 40, and the lower winding of relay 41.

It is noted that the release trunk conductor 97 extending to the first selector switch D, Fig. 2, is connected to this circuit at a point midway between relays 40 and 41. In addition to the operations described, switching relay 40 disconnects ground from armature 64 of relay 42 by means of its armature 67, opens the release magnet circuit at armature 59, extends the starting wire 80 to armature 70 of the line relay 43 by means of armature 60, and by means of armatures 56 and 61 connects up the line wipers 90 and 92. By the latter operation the line conductors 11 and 12 are extended by way of bank contacts 30 and 32, wipers 90 and 92, armatures 56 and 61 and their

working contacts, trunk conductors 96 and 98, and armatures 114 and 116 of the switching relay 104 of the first selector D to the line relay 100, and to ground, respectively.

When the calling line is extended to the selector D in the manner above explained, the line relay 100 is energized over the line circuit, and closes a circuit for the slow acting release relay 101. Upon energizing, the latter relay prepares a circuit for slow acting relay 102 at armature 108, and at armature 107 connects ground to the release trunk conductor 97, thereby establishing a holding circuit which may be traced by way of the said conductor 97, and through the winding of the switching relay 40 of the finder switch F to battery, and also by way of armature 58 and its working contact, private wiper 91, bank contact 31, and armature 19 and its working contact, and the cut-off winding of relay 16 to battery. This holding circuit serves to maintain relays 40 and 16 energized throughout the duration of the connection. Ground is also placed upon the private normal conductor 14 which extends to multiply connected test contacts in the banks of the connector switches which have access to the line of substation A, thereby guarding the line against intrusion in the usual manner. An instant after the holding circuit is established, the line relay 42 of the finder switch F is deenergized, its circuit having been broken by the operation of the switching relay 40. Upon deenergizing, relay 43 disconnects the test wipers 93 and 94 and breaks the circuits of relays 44 and 45, and also disconnects ground from the lower winding of relay 41. In addition, at its armature 70, relay 43 extends the starting wire 80 by way of starting wire 81 to the third finder switch of the group. If none of the other lines terminating in the second level are calling at this time the tens relay 17 will already have been deenergized and ground will have been removed from the starting wire 80. If, however, some other line in the second level is calling relay 17 will remain held up and the third finder switch will be started and will operate to connect with the calling line in the same way as has just been described in the case of the finder switch F.

The foregoing operations by which the line of substation A has been extended through the medium of the finder switch F into connection with the first selector D have all occurred automatically responsive to the removal of the receiver from the hook. The calling subscriber may now operate his calling device in accordance with the first digit in the desired number, which is the digit 4. As a result four interruptions are produced in the line circuit and the line relay 100 at the selector D is deenergized momentarily four times. Although its circuit is broken

momentarily at each deenergization, the slow acting relay 101 remains in operated position and a series of four impulses are transmitted to the slow acting relay 102. The latter relay is accordingly operated and retains its armatures attracted until the series of impulses cease. When the release trunk conductor 97 was first grounded, a circuit was completed by way of armature 111 and 10 its resting contact, the winding of wiper switching relay 105, and the winding of relay 103 to battery. Relay 105 is accordingly now in operated position, but since this relay is of high resistance, relay 103, which 15 is of relatively low resistance and is marginally adjusted, is not operated. Now when the slow acting relay 102 energizes responsive to the impulses received from the line relay 100 it connects the grounded release trunk conductor 97 to the junction of relays 105 and 103, thereby short circuiting the former relay and closing a direct circuit for the latter relay which thereupon energizes. Upon attracting its armature 111, 20 relay 103 closes a locking circuit for itself by way of the resistance 127, and at armature 112 prepares a circuit for the switching relay 104, and at its armature 113 prepares the usual testing circuit. Relay 105 is 25 short circuited when relay 102 is first energized, and since the latter relay remains in operated position while four impulses are being transmitted to it the short circuit is maintained long enough to cause relay 105 to 30 fall back. In doing so it breaks the connection to the release trunk at armature 118 and since its initial energizing circuit has already been opened at armature 111 of relay 103, relay 105 cannot again be operated. 35 Thus it will be seen that the wiper set comprising wipers 121, 122, and 123 are connected for use. At the end of the series of impulses, relay 102 falls back and at its armature 109 completes a circuit extending 40 through the switching relay 104, and the stepping magnet 128, in series to battery. At the same time, at its armature 110 relay 102 connects the test wiper 122 to the above circuit at a point midway between the said 45 relay and magnet. The operation now depends upon whether the test wiper 122 is in engagement with a grounded test contact, or not. If the trunk line terminating in the bank contacts upon which the wiper 50 set in use is standing is busy, the test contact engaged by the test wiper 122 will be grounded, the switching relay 104 will be short circuited, and the stepping magnet 128 being supplied with direct ground by way 55 of the test wiper will operate as a buzzer to advance the switch wipers step by step in search of an idle trunk line. This movement will continue as long as the test wiper 122 engages grounded test contacts, but in 60 the present case we may assume that when the selector D is taken for use wipers 121, 122, and 123 are standing upon the contact set in which is terminated the trunk line extending to the second selector E, and it may be assumed furthermore that this trunk line 65 is idle. Under these circumstances when the slow acting relay 102 falls back and closes the circuit of the switching relay 104, said relay will not be short circuited and no rotary movement of the switch will take 70 place, but the said relay 104 will pull up at once in series with the stepping magnet 128, the magnet remaining inoperative, due to the high resistance of the switching relay. Upon 75 energizing, relay 104 connects grounded release trunk conductor 97 to the test wiper 122 at its armature 115, and at its armatures 114 and 116 disconnects the incoming trunk conductors 96 and 98 from the line relay 100, and from ground, respectively, and extends 80 them by way of the working contacts of the armatures named, armatures 117 and 120 and their resting contacts, wipers 121 and 123, bank contacts 130 and 132, and armatures 160 and 163 and their resting contacts to 85 line relay 151 of the second selector E and to ground, respectively. 90 When the calling line is extended to the second selector E in this manner, line relay 151 is energized over the line circuit and 95 closes a circuit for the slow acting release relay 152. Upon energizing, the latter relay prepares a circuit for the vertical magnet 155 at its armature 165, and at its armature 164 closes a holding circuit which extends 100 from ground by way of the working contact of armature 164 and said armature, release trunk conductor 134, test contact 131, test wiper 122, resting contact of armature 119 and the said armature, working contact 105 of armature 113 and the said armature, resting contact of armature 110 and the said armature, armature 115 and its working contact, working contact of armature 112 and the said armature, and resting contact of armature 109 and the said armature to the release trunk conductor 97 where it joins the previously described holding circuit 110 extending back to the finder switch F, and the cut-off winding of relay 16. This holding circuit is established before the slow acting release relay 101 of the selector D has 115 had time to deenergize, and serves to maintain relays 103 and 104 energized during the connection. 120 It may be well to pause a moment at this point and consider the operation of the selector D a little more fully. The system herein contemplated has a capacity of 2,000 lines, comprising two groups, which may be termed the 1,000 group and the 4,000 group. In other words, the first digit in the telephone numbers assigned to one of the groups of lines is always the digit 1, while the first 125 digit in the telephone numbers assigned to 130

the other group of lines is the digit 4. When the selector D is taken for use, the wiper switching relay 105 is immediately energized by the grounding of the release trunk conductor 97 and locks itself at its armature 118. Then, if the first digit in the desired number is the digit 4, the said relay 105 will be short circuited long enough during the transmission of a series of impulses corresponding to said digit to cause it to fall back, break its locking circuit, and connect up the normally connected set of wipers, all as described in detail in the foregoing paragraphs. However, if the first digit in the desired number is the digit 1, relay 105 will be short circuited only momentarily, and since this relay is slow acting it will not fall back but will remain locked up by way of its armature 118, notwithstanding the fact that its initial energizing circuit is broken at armature 111 of relay 103, and the wiper set comprising wipers 124, 125, and 126 will remain connected for use. The subsequent operation of selecting an idle trunk will take place the same as in the other case, except that since the alternative wiper set is being used a trunk line will be used which extends to a second selector in a different group. It will be seen then that the selector D may have access to two different groups of second selectors corresponding to the two different thousands, and although this is a small number as compared to the usual ten groups which are accessible to the ordinary standard type of first selector, yet under certain circumstances two thousand groups are all that is required, and in such a case a switch of this type is very desirable. The selector D has no complicated stepping mechanism such as is used in the ordinary selector switch and is, therefore, much cheaper to construct. It also has a decided advantage in that its wipers are normally in engagement with a set of bank contacts, and in the majority of cases no rotary movement of the switch is required.

Proceeding now with the explanation, the connection has been extended as far as the second selector E. When the calling subscriber operates his calling device in accordance with the next digit in the number, which is the digit 5, a series of five interruptions is produced in the circuit of the line relay 151 and said relay is accordingly de-energized momentarily five times. At each deenergization of the line relay an impulse of current is transmitted through the slow acting series relay 153 and the vertical magnet 155, and the latter is operated in the usual manner to raise the switch shaft step by step until the wipers 180, 181, and 182 stand opposite the fifth level of bank contacts. Relay 153 is energized in series with the vertical magnet and since it is slow act- ing it retains its armature attracted until the impulses cease. At the end of the vertical movement of the switch, relay 153 is deenergized and since the off normal springs 158 have been closed (these springs are closed at the first upward movement of the shaft) a circuit is completed for the rotary magnet 156 as follows: From the grounded armature 162 by way of the said armature and its resting contact, armature 168 and its working contact, off normal springs 158, armature 166 and its resting contact, armature 167 and its resting contact, and the winding of the rotary magnet 156 to battery. The rotary magnet is accordingly operated and advances the switch wipers into engagement with the first set of contacts in the level opposite which they have been raised. In operating, the rotary magnet closes a circuit for the interrupter relay 154. Upon energizing, relay 154 connects the test wiper 181 with the lower winding of the switching relay 150 at armature 168, and at the same time, or a little later, preferably, breaks the circuit of the rotary magnet at armature 167. The operation now depends upon whether the first trunk line in the selected level is busy or idle. If this trunk line is busy, the test contact engaged by the test wiper 181 will have a ground potential upon it, and since the lower winding of relay 150 is connected to ground the said relay 150 will not be operated. The rotary magnet deenergizes when its circuit is broken at armature 167 and breaks the circuit of the interrupter relay 154 which accordingly falls back and again completes the rotary magnet circuit, the rotary magnet being again operated to advance the switch wipers into engagement with the next set of bank contacts. This operation will continue until the test wiper 181 arrives at a test contact having a battery potential upon it, the battery potential indicating that the associated trunk line is idle. Assuming that the first idle trunk line is the one shown in the drawing; when the test wiper 181 arrives at test contact 184, and relay 154 pulls up responsive to the closure of its circuit by the rotary magnet, a circuit will be completed for the switching relay 150 which extends from ground by way of the lower winding of relay 150, armature 168 and its working contact, test wiper 181, test contact 184, release trunk conductor 187, armature 216 and its resting contact, armature 227 and its resting contact and the upper winding of the line relay 201 of the connector H to battery. Upon the closure of the above circuit, relays 201 and 150 are energized in series and the latter relay closes a locking circuit for itself at its armature 161, at the same time connecting the grounded release trunk conductor 134 to the test wiper 181.

in order to make the selected trunk line busy. Relay 150 also breaks the rotary magnet circuit at its armature 162, and at its armatures 160 and 163 extends the incoming trunk 5 conductors by way of wipers 180 and 182, bank contacts 183 and 185, trunk conductors 186 and 188, and the normally closed contacts at the reversing relay 200 to the upper and lower windings of the line relay 201 of 10 the connector H.

When the calling line is extended to the connector in this manner, the line relay 201 is energized over the line circuit and closes a circuit for the slow acting release relay 15 202. Upon energizing, the latter relay prepares a circuit for the vertical magnet at its armature 215, and at its armature 216 connects ground to the release trunk conductor 187, thereby establishing a holding circuit 20 which may be traced by way of the said conductor 187, test contact 184, test wiper 181, and the make contacts at armature 161 to the release trunk conductor 184, where it joins the previously described holding circuit 25 extending back through the selector D and the finder switch F. The upper winding of the switching relay 150 is connected to the holding circuit at armature 161, and this relay is, therefore, held up throughout 30 the duration of the connection.

The calling subscriber may now operate his calling device in accordance with the next digit in the desired number. As a result six interruptions are produced in the 35 line circuit in the usual manner and the line relay 201 is deenergized momentarily six times, at each deenergization sending an impulse of current through the slow acting relay 203 and the vertical magnet 208 in series. By the operation of the vertical magnet, the connector shaft is raised step by 40 step until the wipers are raised opposite the sixth level of bank contacts. The slow acting relay 203 is energized in series with the vertical magnet and retains its armature 217 attracted during the series of impulses, thereby preventing the vertical magnet circuit from being opened by the shifting of 45 the off normal springs 211, 212 and 213, which takes place at the first upward movement of the switch shaft. At the end of the 50 vertical movement of the switch, the slow acting relay 203 falls back and transfers the operating circuit to the rotary magnet 55 209.

The calling subscriber may now operate his calling device for the next and final digit in the number, this being the digit 7. In response to the interruptions thus produced in 60 the line circuit the line relay 201 is deenergized momentarily seven times, and at each deenergization transmits an impulse of current through the rotary magnet 209. By the operation of the rotary magnet the

switch wipers 250, 251, and 252 are rotated 65 step by step and are finally brought to rest in engagement with the particular set of bank contacts in which the line of substitution A' is terminated, these contacts being indicated by the reference characters 253, 254, 70 and 255. The slow acting relay 206 is connected to the operating circuit and is energized in parallel with the rotary magnet 209, its armatures being held up continuously throughout the rotary movement of the 75 switch. At armature 225, relay 206 connects the test wiper 251 to the winding of the test relay 205, and at its armature 224 relay 206 closes a shunt around the break contact at armature 222 of the test relay, the latter operation being a precautionary measure which prevents the rotary magnet circuit from being opened in case the test wiper should engage a grounded contact 80 while the switch is rotating.

It may be assumed first that the called line is busy when connected with, as explained above. Under these circumstances, when the test wiper 251 comes to rest in engagement with test contact 254 it will find 90 a ground potential thereon and the test relay 205 will be energized. An instant later, when the slow acting relay 206 falls back at the end of the rotary movement of the switch, the test relay establishes a locking circuit for itself at its armature 221. The test relay also breaks the rotary magnet circuit at its armature 222, and at its armature 223 connects a lead from the busy 95 signalling machine to the lower side of the calling line. By this operation an audible 100 busy signal is transmitted to the calling subscriber, and being thus advised that the desired called line is for the time being inaccessible, he will replace his receiver.

Let us assume now that the desired line is idle when called. In this case, when the test wiper 251 arrives at the test contact 254 it will find no ground potential and the test relay 205 will not be energized. Then, when the slow acting relay 206 falls back 110 an instant later, a circuit is completed for the switching relay 207 over the following path: From the grounded release trunk conductor 187 by way of armature 221 and its resting contact, upper winding of relay 207, resting contact of armature 225 and the said armature, test wiper 251, test contact 254, private normal conductor 264, and the cut-off winding of the combination line and cut-off relay 270 to battery. Relays 207 and 270 are energized in series upon the completion of the above circuit, and the latter relay operates to disconnect the conductors 115 260 and 261 of the called line from their normal battery, and ground connections at the exchange. In the connector, when the switching relay 207 is energized it estab- 120 125

lishes a locking circuit for itself at its armature 229, grounds the test wiper 251 at armature 228, breaks the connection at its armature 227 which extends from the upper winding of the line relay 201 to the resting contact of armature 216, opens the rotary magnet at armature 230, and at armatures 226 and 231 connects up the upper and lower line wipers 250 and 252. Ringing current 10 from the generator GEN is now projected intermittently out over the called line in order to operate the bridged ringer at substation A'. The return path for the ringing current includes the upper winding of the ring cut-off relay 204, and when the called subscriber answers the ring cut-off relay is energized, establishing a locking circuit for itself at its armature 219. In addition, relay 204 breaks the ringing circuit 15 at its armatures 218 and 220 and at the working contacts of these same armatures finally completes the talking connection.

The desired connection has now been established and the calling and called subscribers may converse as desired. The transmitter at the calling station A is supplied with talking current through the windings of the double wound line relay 201 of the connector H, while the transmitter at the called station A' is supplied with talking current through the windings of the double wound back bridge relay 200. The latter relay is energized immediately following the energization of the ring cut-off relay 204 and reverses the direction of current flow in the calling line. This operation is of no particular utility in connection with the apparatus shown herein, but is a standard operation provided for in order to control measured service equipment where such equipment is furnished.

At the end of the conversation, both subscribers will hang up their receivers. The release of the connection is controlled by the replacement of the receiver at the calling substation A in the following manner: When the receiver is hung up, the line and release relays 201 and 202 of the connector H are deenergized and jointly close a circuit for the release magnet 210, which operates to restore the connector to position in the usual manner. Relay 202 also breaks the holding circuit extending back to the selectors E and D, finder switch F, and the cut-off winding of the combination line and cut-off relay 16, and all relays in the switches named which have been held up over the grounded holding circuit are permitted to deenergize. At the selector E, 50 when the switching relay 150 falls back a circuit is completed for the release magnet 157, which operates to restore the selector switch to normal position. In the selector D the wipers are not restored; relays 103 and 104 simply fall back, and the latter re-

lays disconnects the wipers. In the finder switch F, when the switching relay 40 is deenergized it closes a circuit for the release magnet 51, which extends by way of the grounded armature 69 and its resting contact, resting contact of armature 59 and the said armature, rotary off normal spring 53 and its working contact, and the winding of the release magnet 51 to battery. By the operation of the release magnet 51 the switch shaft is restored to its normal position, and roller 321 which is carried by the member 310 on the auxiliary shaft 312 is again locked at the latch of armature 322. It is noted that the off normal spring 53, whose function it is to break the release magnet circuit after the switch has been fully restored, is operated on the first rotary movement of the main shaft, rather than on the first vertical movement as is the usual case and this is necessary on account of the fact that the line and private wipers of the finder switch normally stand opposite the first level of bank contacts, from which it will be seen if the calling line is a line terminating in the first level no vertical movement of the switch will take place. Therefore, the off normal spring 53 is arranged to be operated on the first rotary movement, as stated, in order to insure that it will be actuated in all cases.

Having described my invention, what I consider to be new and desire to have protected by Letters Patent will be pointed out in the appended claims.

What I claim as my invention is:

1. In a switching device for automatic telephone systems, the combination with a contact member adjustable and movable in only two directions, of two devices for controlling the adjustment of said member in said two directions, respectively, and means for operating said devices simultaneously.

2. In a switching device for automatic telephone systems, the combination, with a traveling contact member movable in two directions, of mechanism for moving said member in one direction, another mechanism operable simultaneously with said first mechanism for determining the extent of movement in the other direction, and means for delaying the movement of said contact member in the other direction until after the movement in the first direction is completed.

3. In a switching device for automatic telephone systems, a pair of wipers movable simultaneously in different directions, and a third wiper movable simultaneously with one of said first wipers and in the same direction, and movable subsequently in the same direction as the other of said first wipers.

4. In a switching device for automatic telephone systems, a shaft movable vertically and rotarily, stepping magnets for

raising and rotating said shaft, a vertical ratchet rotatable on said shaft, and a rotary ratchet slidable on said shaft vertically.

5. In a switching device for automatic telephone systems, a shaft movable vertically and rotarily, a vertical ratchet rotatable on said shaft, a rotary ratchet slidable on said shaft, and stepping magnets and armatures therefor cooperating with said ratchets to raise and rotate said shaft simultaneously.

6. In a switching device for automatic telephone systems, a wiper shaft, supporting means for said shaft permitting simultaneous longitudinal and rotary movement thereof, a magnet for moving said shaft longitudinally, a second magnet for rotating said shaft, and circuit connections for operating said magnets simultaneously.

20 7. In a switching device for automatic telephone systems, a main shaft, means for moving said shaft longitudinally, and means for rotating it, an auxiliary shaft, means for causing said auxiliary shaft to move longitudinally with said main shaft, and means for rotating said auxiliary shaft after the rotation of the main shaft has ceased.

30 8. In a switching device for automatic telephone systems, a main shaft and an auxiliary shaft, means for moving both shafts longitudinally, means for rotating the main shaft, means for locking the auxiliary shaft against rotation, and means for releasing the auxiliary shaft after the rotation of the main shaft is completed.

40 9. In a switching device for automatic telephone systems, a main shaft, an auxiliary shaft rotatable on said main shaft, means causing said auxiliary shaft, when unrestrained, to assume a normal position relative to said main shaft, means for moving both shafts longitudinally, means for rotating the main shaft, means for locking the auxiliary shaft against rotation, and means for releasing the auxiliary shaft to permit it to assume its normal position.

50 10. In a telephone system, an automatic switch having primary and secondary group and line selecting movements, means whereby said switch is caused to perform both movements simultaneously, and means for operating said switch in a tertiary movement to an extent determined by the secondary movement to connect with the selected line.

60 11. In a telephone system, a plurality of groups of lines, a switch having vertical movement to select a group and rotary movement to select a line in the selected group, and means for causing said switch to perform both movements simultaneously.

65 12. In a telephone system, a plurality of groups of lines, an automatic switch having group and line selecting movements whereby any line in said groups may be selected,

means for causing said switch to perform both of said movements simultaneously, and means for rendering the line selecting movement ineffective until after the group selecting movement is completed.

70 13. In a telephone system, an automatic switch for use in connecting calling and called lines, primary and secondary operating magnets in said switch for operating the same to establish a connection, means for operating said magnets simultaneously, a connecting wiper in said switch directly responsive to said primary magnet, and a trip magnet for causing said wiper to respond to said secondary magnet.

75 14. In a telephone system, an automatic switch for use in connecting a calling and called line, a movable contact member in said switch adjustable only in two directions at right angles to each other to close a contact in the talking circuit, primary and secondary operating magnets governing the adjustment of said member in said two directions, respectively, and means for simultaneously actuating said magnets to perform their respective functions as set forth.

80 15. In a telephone system, an automatic switch for connecting lines, and a wiper in said switch having step by step primary selecting movement and continuous secondary selecting movement.

85 16. In a telephone system, an automatic switch adapted to perform successive group and line selecting operations for connecting lines, a wiper in said switch, means for giving said wiper a step by step movement during a group selecting operation, means for preventing movement of said wiper during a line selecting operation, and means for giving said wiper a continuous movement after the line selecting operation is completed.

90 17. In a telephone system, an automatic switch for use in connecting lines, a line wiper in said switch having successive primary and secondary movements, and primary and secondary test wipers movable simultaneously to determine the movement of said line wiper.

105 18. In a telephone system, a group of lines, a finder switch for extending calling lines in said group, wipers in said switch having primary and secondary selective movements, respectively, to locate a calling line, and means whereby both of said selecting movements are performed simultaneously.

110 19. In a telephone system, a plurality of groups of lines, a finder switch for extending calling lines in said groups, wipers in said switch having group and line selecting movements, respectively, and means for causing both said selecting movements to be performed simultaneously.

120 20. In a telephone system, subscribers'

- lines, a finder switch for extending said lines when calling, primary and secondary operating magnets in said switch, means for operating said magnets simultaneously responsive to a call to cause said finder to locate the calling line, and means including a two motion wiper shaft controlled by said magnets for connecting with a calling line when the same is located.
- 10 21. In a telephone system, subscribers lines, a finder switch for extending said lines when calling, primary and secondary test wipers movable simultaneously to locate a calling line, and line wipers movable first primarily and then secondarily to complete the connection.
22. In a telephone system, groups of lines, a finder switch for extending said lines when calling, means for starting said switch responsive to a call, common group and unit test contacts in said switch, group and unit test wipers in said switch cooperating with said contacts to stop said switch on the calling line or on another line having a lower units designation, and means for automatically restarting said switch in case the line on which the switch is stopped is not calling.
23. In a telephone system, groups of lines, a finder switch for extending said lines when calling, means for starting said switch responsive to a call, common group and unit test contacts in said switch, group and unit test wipers in said switch cooperating with said contacts to stop said switch on the calling line, and means for automatically restarting said switch in case it is stopped on the wrong line by a second calling line in a different group.
24. In a switching device for automatic telephone systems, a contact member, supporting means for said member restricting it to movement in two perpendicular planes, and simultaneously operable means for controlling the extent of said movements.
25. In a switching device for automatic telephone systems, a wiper having movement in only one direction, a second wiper having movement in only one direction, but in a different direction from the direction of movement of said first wiper, electromagnetic mechanism for moving said wipers simultaneously, and a third wiper movable under control of both said first and second wipers.
26. In a finder switch, a line wiper, primary and secondary test wipers, and means for progressively advancing said test wipers simultaneously to cause the switch to locate a calling line and engage the same with said line wiper.
27. In a switching device for automatic telephone systems, vertical and rotary operating magnets, and a shaft arranged for simultaneous vertical and rotary movements under control of said magnets.
28. In a switching device for automatic telephone systems, vertical and rotary operating magnets, armatures and pawls for said magnets, a rack engaged by the vertical pawl, a ratchet wheel engaged by the rotary pawl, and a shaft which is lifted and rotated simultaneously by said rack and ratchet, respectively.
29. In a telephone system, a plurality of lines, a finder switch, means for starting and stopping said finder, a restarting circuit closed automatically whenever the switch is stopped, a test circuit closed at the same time as said restarting circuit, and means controlled over said test circuit for rendering the restarting circuit ineffective in case the line upon which the finder is stopped is a calling line.
30. In a telephone system, a plurality of lines, a finder having primary and secondary movement, means common to said lines for causing the advance of said finder in two separate movements to a line designated by said common means, separate means in said finder for testing the line so located to ascertain whether it is calling or not, and means for automatically restarting said finder in case the line is not calling.
31. In a telephone system, a plurality of lines, a finder switch, means common to said lines for designating calling lines, means individual to each line for designating such line as a calling line, means for starting said finder responsive to a call, test relays in said finder controlled by said common means to stop the finder upon a designated line, and another test relay in said finder controlled by said individual means to cause the finder to connect with the line upon which it has stopped provided such line is actually calling.
32. In a telephone system, a plurality of groups of lines, a finder switch, common group and unit test contacts in said switch, an individual test contact in said switch for each line, group and unit test wipers in said switch co-operating with said common test contacts, and another test wiper in said switch co-operating with said individual test contacts.
33. In a telephone system, a plurality of groups of lines, a finder switch, common group and unit test contacts in said switch, an individual test contact in said switch for each line, group and unit test wipers in said switch co-operating with said common test contacts, another test wiper in said switch co-operating with said individual test contacts, and circuit arrangements such that all three test wipers are used to definitely stop said finder on a calling line.
34. In a telephone system, a plurality of groups of lines, a finder switch, common group and unit test contacts in said switch, an individual test contact in said switch for

each line, group and unit test wipers in said switch co-operating with said common test contacts, another test wiper in said switch co-operating with said individual test contacts, means in said finder controlled over said group and unit test wipers for tentatively stopping the finder on a supposed calling line, and means in said finder for making the stop a definite one in case the line 10 is actually calling.

35. In a telephone system, a plurality of lines, a finder switch, common tens and units relays for indicating calling lines to said finder, and means for causing said finder 15 to pass by a non-calling line having the same tens designation as a calling line for which the finder is hunting and the same units designation as a second calling line.

36. In a telephone system, a plurality of 20 lines, a finder switch operating according to the rectangular coordinate system, a device common to each group of lines of which the ordinates are the same, a device common to each group of lines of which the abscissas 25 are the same, means whereby any line when calling causes the operation of the devices assigned to the respective groups to which such calling line belongs, the two operated devices being effective to designate the calling 30 line to said finder, means whereby another calling line causes the operation of two more of said devices, and means for causing said finder to pass by a non-calling line which is falsely indicated as calling by 35 one of the devices operated by the first calling line in conjunction with one of the devices operated by the second calling line.

37. In a telephone system, a plurality of 40 lines, tens relays, each common to a group of said lines having the same tens designations, units relays each common to a group of said lines having the same units designa-

tions, a line relay individual to a line and connected in series with the units and tens relays which correspond to the groups to 45 which such line belongs, and a similarly connected line relay for each of the remaining lines.

38. In an automatic switch, two shafts, a spring connecting said shafts, electro-magnetic means for driving one shaft to a definite point while the second shaft is held 50 against movement, and means for releasing the second shaft to permit the same to follow said first shaft under tension of said 55 spring.

39. In an automatic switch, two shafts, a spring connecting said shafts, electro-magnetic means for driving one shaft, means for holding the second shaft, and means for 60 releasing said second shaft during the movement of said first shaft, whereupon the said second shaft is impelled by said spring to overtake said first shaft and thereafter partake in its movement.

40. In a telephone system, subscribers' 65 lines, a finder switch for extending any line when calling, a test contact individual to each line, a test wiper in said finder, means for altering the electrical condition of the 70 test contact belonging to a calling line when said finder is started, means for stopping said finder responsive to the arrival of said test wiper on any test contact whose electrical condition has been altered, and means 75 for automatically restarting said finder in case the same is stopped with its test wiper in engagement with a test contact whose electrical condition has been altered due to some cause other than that the associated 80 line is calling.

Signed by me at Chicago, Cook County, Illinois, this 15th day of Nov. 1920.

RODNEY G. RICHARDSON.
